(57) **CLAIM**

The ornamental design for a fuel collection and evaporation mat, as shown and described.

DESCRIPTION

FIG. 1 is a top perspective view for a fuel collection and evaporation mat showing my new design;

FIG. 2 is a top side view thereof;

FIG. 3 is a left side view thereof;

FIG. 4 is a right side view thereof;

FIG. 5 is a bottom side view thereof;

FIG. 6 is a front side view thereof;

FIG. 7 is a rear sectional view taken along lines 7-7 from FIG. 2 thereof;

FIG. 8 is a partially enlarged sectional rear view thereof, taken from FIG. 7 thereof; and,

FIG. 9 is a partially enlarged top perspective view thereof, taken from FIG. 1.

The even-length broken lines within FIGS. 1, 2, 5 and 9 represent stitching and form no part of the claimed design. The broken lines in FIGS. 1 and 7 are included to show partially enlarged views only and form no part of the claimed design.

The broken line indicia in FIGS. 1 forms no part of the claimed design.
